CLAIM

The ornamental design for a tablet, as shown and described.

DESCRIPTION

FIG. 1 is a perspective view of a tablet showing my new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is an enlarged view thereof, showing the encircled portion 9 in FIG. 2.

The broken lines depict portions of the tablet and form no part of the claimed design.

The dash-dot-dash lines in FIGS. 2 and 9 depict an enlarged view only and form no part of the claimed design.
